(57) **CLAIM**

The ornamental design for a pulse oximeter, as shown and described.

DESCRIPTION

FIG. 1 is a front perspective view of a pulse oximeter in accordance with our new and ornamental design;

FIG. 2 is a front view of the pulse oximeter shown in FIG. 1;

FIG. 3 is a rear view of the pulse oximeter shown in FIG. 1;

FIG. 4 is a left side view of the pulse oximeter shown in FIG. 1;

FIG. 5 is a right side view of the pulse oximeter shown in FIG. 1;

FIG. 6 is a top plan view of the pulse oximeter shown in FIG. 1;

FIG. 7 is a bottom plan view of the pulse oximeter shown in FIG. 1;

FIG. 8 is another front perspective view of the pulse oximeter, shown in an open configuration;

FIG. 9 is a front view of the pulse oximeter shown in FIG. 8;

FIG. 10 is a rear view of the pulse oximeter shown in FIG. 8;

FIG. 11 is a left side view of the pulse oximeter shown in FIG. 8;

FIG. 12 is a right side view of the pulse oximeter shown in FIG. 8;

FIG. 13 is a top plan view of the pulse oximeter shown in FIG. 8; and,

FIG. 14 is a bottom plan view of the pulse oximeter shown in FIG. 8.

(Continued)

The broken lines in the drawing illustrate portions of the pulse oximeter that form no part of the claimed design.
